Primary Examiner — Elizabeth Albert(74) *Attorney, Agent, or Firm* — Kenneth H. Jack; Davis & Jack, LLC(57) **CLAIM**

The ornamental design for a pencil sharpener, as shown and described.

DESCRIPTION

FIG. 1 is a perspective view of the pencil sharpener showing my new design.

FIG. 2 is another perspective view of the pencil sharpener of FIG. 1; and,

FIG. 3 is a left side elevational view of the pencil sharpener of FIG. 1.

(The broken lines appearing in FIGS. 1, 2, and 3 showing a pencil and showing other features are included for the purpose of illustrating environmental matter and form no part of the claimed design.)

The intended use of the article in which the design is embodied is the sharpening of pencils.

A feature of the article in which the design is embodied is its depiction or configuration as a stentor or megaphone.
